UNITED STATES PATENT OFFICE.

JONATHAN PERKINS, JR., OF SAN DIEGO, CALIFORNIA.

GRAVITY-ACTUATED PIPE-LAYING APPARATUS.

1,139,440.

Specification of Letters Patent. Patented May 11, 1915.

Application filed June 2, 1913. Serial No. 771,202.

To all whom it may concern:

Be it known that I, JONATHAN PERKINS, Jr., a citizen of the United States, and a resident of San Diego, county of San Diego, State of California, have invented a certain new and useful Gravity-Actuated Pipe-Laying Apparatus, of which the following is a specification.

My invention relates to an apparatus for handling and placing in position the different sections of pipe, preferably concrete pipe and the objects of my invention are, first, to provide an apparatus to facilitate the laying of large pipe, second, to provide such an apparatus that is simple, easily constructed and easily operated, and third, to provide such an apparatus in which the parts are adjustable for different sized pipe sections.

With these and other objects in view, as will appear hereinafter, my invention consists of certain novel features of construction, combination and arrangement of parts, as will be hereinafter described in detail and particularly set forth in the appended claims, reference being had to the accompanying drawings and to the characters of reference thereon, which form a part of this specification, in which:

Figure 1 is a side elevational view of my device in the preferred form shown in connection with the pipe section with parts of the pipe broken away and in section to facilitate the illustration, Fig. 2 is an end view of the pipe showing the tripod in position, Fig. 3 is a side elevational view of my pipe carriage shown mounted on a fragmentary portion of this support and showing a section of pipe mounted thereon in section, Fig. 4 is a top or plan view of a fragmentary portion of said carriage, Fig. 5 is a transverse sectional view taken through A—B of Fig. 3.

Similar characters of reference refer to similar parts throughout the several views.

The tripod 1, carriage 2, carriage support 3, and jack 4, constitute the principal parts of my device.

The tripod 1, consists of a straight portion threaded almost its entire length and bifurcated at its top end 1^a. It is mounted in a support 1^b which is provided with an internal thread adapted to fit the thread on the screw on the main portion 1. Over this thread in the main portion 1 is provided a nut 1^c on

which are rigidly mounted at angles to said main portion 1, legs 1^d and 1^e which are adjustably mounted in supports 1^f. Mounted on this tripod in the slot between the bifurcated members 1^a is a T bar 3 adapted for the support for the carriage 2. Over this support is mounted the body portion 2 of the carriage, shaped as shown best in Figs. 3 and 5. It is provided with two longitudinal axis rollers 2^a adapted for supporting the pipe section, which section may be turned thereon. It is supported by means of two transverse axis rollers 2^b which are provided with flanges adapted to roll on the upper surface of the support 3 to reduce the friction of the movement of the carriage. The other end of the support from the tripod is supported by means of the jack 4 which is an ordinary jack except that it is provided with bifurcated top ends 4^a adapted to fit the downwardly extending member of the support 3.

It is obvious that with this apparatus there is provided a device that will greatly facilitate the placing of the different sections of pipe, that by adjusting the tripod 1 to the proper height, placing the support with the carriage thereon through the pipe section, placing a jack 4 under the other end and raising the end, that the pipe section, being mounted on the carriage as shown best in Figs. 1, 3 and 6, will gravitate to its proper position after which the jack may be lowered and the operation repeated, that the rollers 2^a on the carriage will allow the pipe to be revolved thereon if desired, and that the apparatus is simple of construction and easily operated.

Having thus described my invention, what I claim as new and desire to secure by Letters Patent, is:

1. In a gravity actuated pipe laying apparatus an adjustable tripod, a normally horizontal bar with one end mounted thereon, a carriage mounted on said bar and provided with rollers to facilitate its movement thereon, horizontal axis rollers mounted on said carriage so that their upper surfaces extend above said carriage and means for raising and lowering the other end of said bar.

2. A gravity actuated pipe laying apparatus, comprising an adjustable tripod with bifurcated upper end, a normally horizontal T bar with one end mounted thereon, a carriage mounted on said T bar and fitted

around the same and adapted to travel thereon, and a jack the upper end of which is bifurcated to fit said T bar for raising the end thereof.

- 5 3. A gravity actuated pipe laying apparatus, comprising a tripod, each member of which is adjustable, a normally horizontal bar with one end mounted thereon, and adapted to fit the upper end thereof, a carriage provided with horizontal axis rollers,

mounted on said bar and adapted to travel thereon, and a jack which is adapted to fit said bar for raising the other end thereof.

In testimony whereof, I have hereunto subscribed my name in the presence of two subscribing witnesses.

JONATHAN PERKINS, JR.
